UNITED STATES PATENT OFFICE.

WILLIAM A. ZEIDLER, OF NEW YORK, N. Y.

METHOD OF CONNECTING TWO PIECES OF METAL OR LIKE MATERIAL.

1,366,148.

Specification of Letters Patent. Patented Jan. 18, 1921.

Application filed April 24, 1918, Serial No. 230,543. Renewed April 19, 1919. Serial No. 291,415.

To all whom it may concern:

Be it known that I, WILLIAM A. ZEIDLER, a citizen of the United States, residing at New York, in the county of Bronx and State of New York, have invented certain new and useful Improvements in Methods of Connecting Two Pieces of Metal or like Material, of which the following is a specification.

10 This invention relates to method for securely connecting together two pieces of metal or the like material, without welding or riveting or other devices or expedients, and to articles made in accordance with such process.

15 The objects and aims of the invention, together with the advantages inherent, will be in part obvious and in part specifically referred to in the course of the following 20 description of the elements, combinations, arrangements of parts, and applications of principles constituting the invention; and the scope of protection contemplated will appear from the claims.

25 In the accompanying drawings, which are to be taken as part of this specification, and in which I have shown a merely preferred form of embodiment of the invention,

30 Figure 1 is a collective view in plan and edge view showing one of the connected pieces at the first stage of its manipulation under my process; Fig. 2 is a similar view showing the succeeding step; Fig. 3 is a similar view showing the last step, with the other connected pieces in secured position; Fig. 4 is a plan view of two pieces connected in accordance with my invention, and intended for use in connection with a 35 shell fuse shown in Fig. 7; Fig. 5 is an edge view of the subject-matter of Fig. 4; Fig. 6 is a view partly in section and partly in edge view of the safety device for a shell fuse, in connection with which my 40 invention finds a use; and Fig. 7 is a view partly in elevation and partly in section illustrating how the device of Fig. 6 appears when in operative position in a shell fuse.

35 Referring first to Figs. 4, 5, 6 and 7, the numeral 8 indicates a strip of readily flexible metal, which is to be shaped as shown in Figs. 4 and 5 and so that it may be coiled into the form shown in Fig. 6, 45 around about the detonating pin 9 of a shell fuse and between the nose 10 of such

fuse and a shoulder or washer 11. So long as this spiral is in position around the detonating pin it acts as a safety, to prevent accidental inward movement of the pin, 60 and it is contemplated that when the projectile is discharged from the gun its rotation will generate centrifugal force sufficient to strip the spiral away from the pin, so that when thereafter the nose 10 strikes a solid 65 object it will be driven inwardly, after shearing off the relatively soft shearing pin 12. All of this is familiar construction. The actual spacing of the nose 10 and washer 11 is accomplished by means of spacer elements 70 14 shown in Fig. 6. One of these spacer elements 14 has a lug 15 which extends through an appropriate opening in the wall of the strip 8 and engages in a groove 16 of the firing pin, and the outer end of the 75 strip must be made heavier so that centrifugal force may come into play. For the purpose of weighting the outer end of the spiral various expedients have been proposed. For instance, a heavy piece of metal 80 has been riveted to the outer end of the strip 8, but this has the objection that the riveted end sometimes comes off before the spiral is completely stripped. It has also been proposed to weld a heavy piece of 85 metal at the outer end of the strip 8 and this is also unsatisfactory for obvious reasons. According to my invention the weight which is to go upon the outer end of the strip 8 is in the form of a rectangular 90 piece of metal, which is provided with comparatively wide parallel grooves 17. These grooves are formed by an ordinary machining operation or the like, upon the flat piece shown in Fig. 1, and thereafter, 95 as shown in Fig. 2, the sides of the piece beginning with the inner limit of each groove 17 are bent up at right angles or nearly so. The outer end of the strip 8, 100 which is preferably somewhat wider than the surface 18 between the grooves 17, is now introduced between the upstanding sides 19 of the weight-piece, with its edges in the under-cuts provided by the adjacent portions of the grooves 17, and thereupon 105 the sides 19 are forced down toward each other to the position shown in Fig. 3. This causes the end of the strip 8 to assume a transversely bowed condition, with the edges of the strip extending upwardly into the 110 spaces provided by the grooves 17, and the median portion of the strip bowed away

from the floor 18. The frictional grip thus obtained between the weighted end piece and the strip 8 is enormous and the connection has stood up under the most rigid 5 of official tests. Aside from the security of the connection there are obvious advantages favoring rapid quantity production. Thus the end of the strip itself needs no manipulation, the initial preparation of the 10 weight-piece is simple, because the grooves can be machined in a practically endless strip of metal which is then cut off into suitable lengths, and the subsequent bending up of the weight-piece and the bending 15 of it around the end of the strip 8, may all be readily done by means of automatic mechanism and dies. After the parts have been connected as shown in Figs. 3, 4, 5, the union between the connected parts is 20 still further strengthened by the longitudinal bending of the end of the spiral, including the end of the strip 8 and the weight member which grips the end of the strip 8, as indicated at 20 in Fig. 6. When 25 the spiral is in position around the firing pin, and up to the time when the projectile is to be placed in the gun, the spiral is held integral by means of a bit of wire 21 tied around it and with its ends coiled as at 30 22, Fig. 6, this wire being cut before the shell is inserted in the gun. The spacer elements 14 fit in seats 24 formed in the strip 8, and the strip is coiled around them as shown in Fig. 6 so that when the weighted 35 end 20 flies out under centrifugal force and the strip is thrown off, it carries the spacer elements 14 with it.

It has been stated that the end of the strip 8 is wider than the bottom wall 18 of 40 the weight member between the grooves 17. It should be added that the side edges of the end of the strip 8 (Fig. 2) fit snugly between the bottom walls of the grooves 17, so that as these bottom walls move toward 45 each other to the Fig. 3 position the buckling of the end of the strip is accomplished as stated. This transverse buckling of course adds to the force of the grip between the two connected parts. Obviously, instead of first bending up the sides 19 and then inserting the strip between them, the strip 50 may be laid on the flat blank (Fig. 1) and then the bending operations shown in Figs. 2 and 3 proceeded with.

55 It will be noted in Fig. 3 that the meeting edges of the inturned sides 19 provide a groove running longitudinally of the connected parts. This groove, in the final form of the device, Fig. 6, serves as a convenient 60 seat for the binding wire 21.

Inasmuch as many changes could be made in the above construction, and many apparently widely different embodiments of my invention could be made without departing 65 from the scope thereof, it is intended that

all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, 70 might be said to fall therebetween.

I claim:

1. The method of connecting two pieces of metal, one of them in strip form, which consists in providing the other piece with 80 parallel grooves, bending up the sides of the second piece at right angles, beginning with the inner limit of the grooves respectively, introducing the end of the first piece or strip between said upturned sides, with its surface flat against the portion of the second piece between the grooves and its edges fitting snugly between the bottom walls of the grooves, and then bending the sides of the second piece toward each other and 90 down upon the end of the strip, whereby the end of the strip is bowed and gripped between said sides.

2. The method of connecting two pieces of metal, one of them in strip form, which 95 consists in providing the other piece with parallel grooves, bending up the sides of the second piece at right angles, beginning with the inner limit of the grooves respectively, introducing the end of the first piece 100 or strip between said upturned sides, with its surface flat against the portion of the second piece between the grooves and its edges fitting snugly between the bottom walls of the grooves, then bending the sides 105 of the second piece toward each other and down upon the end of the strip, and then bending the two pieces longitudinally.

3. An article of the kind described comprising a weight-piece having a bottom or 110 median portion and two side portions bent toward each other and toward the bottom portion, and a strip of metal having its end gripped between said bottom portion and the side portions, and transversely bowed.

4. An article of the kind described comprising a weight-piece having a bottom or median portion and two side portions bent toward each other and toward the bottom portion, and a strip of metal having its end 120 gripped between said bottom portion and the side portions, and transversely bowed, and the connected parts being longitudinally curved.

5. The method of connecting two pieces 125 of metal, one of them in strip form, and the other in a U-shape form, with the arms on the inner side undercut above their junction with the bottom of the U, inserting the strip between the arms of the U with its 130

edges in the cut-outs thereof, and then bending the arms toward each other, whereby the end of the strip is bowed and gripped between the sides, substantially as described.

5 6. The method of connecting two pieces of metal, which consists in bending up the sides of one piece substantially at right angles, introducing the end of the other piece between said upturned sides, bending 10 the sides of said first piece toward each other and down upon the other piece and then bending the two connected pieces longitudinally.

7. The method of connecting two pieces 15 of metal, which consists in bending inward toward each other the sides of a trough-shaped strip and down upon a second strip disposed in the trough of said first strip and then bending the connected strips longitudinally.

20 8. An article of the kind described, comprising a weight piece and a strip, one of

said members being of generally C-shape form, the other member having a portion disposed within the trough of said C-shape 25 member and the end portions of said C-shaped member bearing upon the interposed portion of the other member, said connected parts being longitudinally curved.

9. An article of the kind described, comprising a weight piece and a strip, one of 30 said members being of generally C-shape form, the other member having a portion disposed within the trough of said C-shaped member and the sides of said C-shaped member being bent toward each other and down upon the interposed portion of the other member, one of said connected parts having 35 on an exposed side thereof a longitudinal groove providing a seat for a binding wire, 40 and a binding wire seated in the groove.

In testimony whereof I affix my signature.

WILLIAM A. ZEIDLER.
